QUICK FREEZING PROCESS

Charles T. Walter, Chicago, Ill., assignor to Industrial Patents Corporation, Chicago, Ill., a corporation of Delaware

Application November 21, 1936, Serial No. 112,177

8 Claims. (Cl. 62—104)

This invention relates to a quick freezing process for foods and to apparatus for carrying out the process.

One of the objects of the invention is to provide an improved quick freezing process.

Another object of the invention is to provide apparatus for carrying out an improved quick freezing process.

Other objects will be apparent from the description and claims which follow.

As is well known, quick freezing involves advantages over slow freezing in that in quick freezing the ice crystals formed in the foods are small and do not rupture the cell walls, avoiding an excessive moisture loss by cellular leakage upon defrosting.

The present invention is particularly adapted for quick freezing poultry.

Embodiments of apparatus involved in the present invention are shown in the drawings.

Figure 1 is a schematic view, partly in section, of one form of apparatus involved in the present invention.

Figure 2 is a side view, partly in section, of another form of apparatus which may be employed in carrying out the process of the present invention.

Referring now more particularly to Figure 1:

Retort 1 is provided with a removable head 2 at one end. Head 2 may be held tightly in position by any suitable means as bolts 3 and wing nuts 4, and is removed to charge the retort with product to be frozen. Product 5 is placed in retort 1 on rack 6. It will be noted that retort 1 is provided with vapor chamber 7 to avoid return of slugs of liquid through pipe 8 to compressor 9.

The present invention is carried out with a suitable liquid refrigerant, as for example liquid carbon dioxide. Before the system is started, air is removed through pipe 10 provided with valve 11. Pipe 8 is provided with valve 12 and returns gaseous refrigerant to compressor 9 from chamber 7 of retort 1. Compressor 9 delivers the compressed refrigerant in gaseous form through line 13 to condenser 14 which may be of any suitable type and is designed to discharge the liquefied refrigerant through pipe 15 into receiver 16. Receiver 16 is preferably of large capacity and should contain enough of the liquefied refrigerant to fill retort 1 to the desired level.

Liquid refrigerant is delivered from the receiver 16 to retort 1 through pipe 17 provided with valve 18 which functions as the control valve for shutting off the receiver 16 from the retort 1, when the retort is to be opened.

Valve 12 is employed for closing the retort off from the compressor. Pump 19 is provided to return to the receiver any liquid refrigerant remaining in retort 1 after completion of the freezing operation prior to opening the retort for removal of the product. Liquid refrigerant in the retort returns to receiver 16 through line 20 provided with valve 21 and line 22 provided with valve 23. Gauge 24 is provided for visual observation of the level of liquid refrigerant in retort 1.

The apparatus shown in Figure 1 may be operated in the following manner:

Assuming valves 12 and 18 are closed and that receiver 16 is filled with liquid refrigerant under suitable pressure and temperature conditions, retort 1 is open at head 2, the desired quantity of product is loaded into the retort and cover 2 tightly closed. Valve 11 is opened slightly to allow air retained in the retort to escape. Valve 18 is next opened and a suitable quantity of refrigerant permitted to flow into retort 1 through pipe 17. A sufficient quantity of refrigerant is admitted to retort 1 to completely cover all product to be refrigerated, the level being observed in gauge 24. When it appears that substantially all air within the retort 1 has been discharged through valve 11, this valve is closed. Pressure is now built up in retort 1. The pressure will depend upon the nature of the refrigerant and the temperature of the product and retort. Valve 18 is closed after a suitable quantity of refrigerant has been admitted to the retort. Compressor 9 is then started and valve 12 opened, starting the pumping down process. As soon as compressor 9 starts to remove gas from retort 1, some of the liquid refrigerant in retort 1 evaporates, reducing the temperature of the mass of liquid refrigerant and the surrounding materials. As the vapor pressure in retort 1 is lowered, the temperature of the refrigerant is lowered. With such refrigerants as liquid carbon dioxide, very low temperatures may be obtained, and consequent rapid chilling of the product in trays 6.

The shell of the retort is heavily insulated against the transfer of atmospheric heat into the system as by insulation 25. Similarly the receiver is heavily insulated as by insulation 26.

As the freezing of the product proceeds, if more refrigerant is desired to maintain complete submersion of the product, the desired quantity may be admitted at will through valve 18.

After freezing has proceeded to the desired extent, valves 21 and 23 may be opened and pump 19 placed in operation to pump the remaining

- liquid refrigerant from retort 1 into receiver 16. After all of the refrigerant in retort 1 has thus been returned to receiver 16, valves 21 and 23 may be closed. Compressor 9 should continue to operate until the pressure in retort 1 has been reduced to atmospheric pressure or less. Compressor 9 may then be stopped and the retort 1 opened with safety to permit removal of the product.
- 10 Any liquid refrigerant which may remain in or about the product will be rapidly and completely evaporated from the product during subsequent handling.
- In the refrigeration of foods, it is essential that the refrigerant be one which is not absorbed and must be one which is relatively inexpensive, non-toxic, convenient to handle, and which has physical and thermal characteristics making possible extremely low temperatures and rapid rates of heat exchange. Liquid carbon dioxide is such a refrigerant.
- Referring now more particularly to Figure 2:
- 15 Retort 1 is provided with head 2 which may be securely fastened to retort 1 by means of bolts 3 and wing nuts 4. Product 5 may be placed upon racks 21. It is understood, of course, that retort 1 must be sufficiently strong to withstand the ordinary working pressures to be imposed upon it. Retort 1 is covered with insulation 25 and receiver 16 is covered with insulation 26. Receiver 16 functions as a liquid receiver and as an evaporator and is connected to retort 1 by pipe 17 provided with valve 18. Chamber 16 is adapted to hold a quantity of liquid refrigerant to any suitable level, the space 28 above the liquefied refrigerant being occupied by the refrigerant in its gaseous state.
- 20 A suitable compressor machine 9 is included in the system to deliver the hot compressed gas to the condenser 14 through pipe 13 where it is liquefied and returned to receiver 16 through pipe 15. Air pump 29 is provided to exhaust chamber 1 of air at the start of the freezing cycle communicating with retort 1 through pipe 30 and pipe 10 provided with valve 31. Pipe 30 is provided with valve 32. Air withdrawn by pump 29 is exhausted through pipe 33. The pump 34, suitable for handling liquid refrigerant, is employed to return quantities of liquid refrigerant from retort 1 to receiver 16 at the end of the freezing process. Pump 34 removes refrigerant from retort 1 through pipe 35 provided with valve 36, and returns the refrigerant from receiver 16 through pipe 37 communicating with pipe 15. Retort 1 is provided with safety valve 38 to prevent damage to the apparatus in the event of excessive pressure.
- 25 During the operation of the system, gas evaporating from the liquid refrigerant in retort 1 is withdrawn through pipe 39 communicating with pipe 40 at 41. Gaseous refrigerant formed in the receiver 16 may also be withdrawn through pipe 40 to compressor 9. Pipe 40 is provided with valve 42 between compressor 9 and 41.
- 30 The operation of the apparatus will be readily understood by reference to Figure 2. Assuming that the receiver 16 is nearly full of liquid refrigerant such as liquid carbon dioxide, the liquid being at room temperature, valves 18 and 32 are closed. Valve 42 is opened and the compressor 9 started. The vapor pressure in space 28 will be reduced and some of the liquid refrigerant will be evaporated. This evaporation will bring about a reduction in the temperature of the remaining refrigerant. As the compressor con-
- tinues to operate, the temperature of the liquid refrigerant continues to lower, concurrently lowering the pressure within space 28. The compressed gas passed into the condenser 14 is liquefied and returned to receiver 16. After a period of time, any desired temperature for the liquid refrigerant may be obtained within the limits of the physical characteristics of the refrigerant. For example, if the liquid refrigerant is carbon dioxide and it is desired to operate at a temperature of 0° F., a pressure of approximately 300 pounds per square inch will be maintained in receiver 16. After the desired temperature of the refrigerant has been reached, it will be maintained while the compressor is operated at the suction pressure corresponding to that temperature.
- 35 Retort 1 is now filled with a quantity of the product to be refrigerated, head 2 tightened in place, and air pump 29 started for the purpose of extracting air from chamber 1 and to avoid the introduction of substantial quantities of unliquefiable gases into the system. If desired, a simple blow-off valve may be provided as a substitute for air pump 29 permitting the valves to remain open after a small quantity of liquid carbon dioxide is introduced into chamber 1. The evaporating carbon dioxide will tend to dispel the air through the blow-off valve, but this method would entail a loss of refrigerant and, consequently, the pump is preferred.
- 40 After the chamber 1 has been well exhausted by the action of air pump 29, valves 18 and 32 are opened, permitting the prechilled liquid refrigerant to enter the retort and completely or partially flood the interior of retort 1. Liquid refrigerant comes in contact with the product to be chilled at the minimum temperature of the refrigerant, causing freezing of the product to commence immediately. Contact of the liquid refrigerant with the warm product results in a heat exchange and the evaporation of some of the liquid refrigerant. The gases thus formed are drawn off through pipe line 39 to the compressor 9, maintaining a minimum temperature of the refrigerant at a constant value.
- 45 The system assures that the maximum pressure in retort 1 is that pressure corresponding to the minimum temperature of the refrigerant. The carbon dioxide operating from 0° to 50° F. the maximum pressure in the chamber will be about 300 pounds. On the other hand, the pressure which may exist in receiver 16 will be much higher than this and will correspond to the vapor pressure of the liquid refrigerant at the highest temperature that may prevail in the receiver, which may be as high as 100° or more F.
- 50 After the system has operated sufficiently to chill or freeze the product to the desired degree, the freezing operation is stopped by closing valves 18 and 32, and starting pump 34, drawing off from the bottom of the retort 1 the liquid refrigerant remaining therein and returning it through pipe 37 to receiver 16. The refrigerant is not heated before being returned to receiver 16, but is returned at approximately its minimum temperature. After all of the liquid has been withdrawn from retort 1, pump 34 may be stopped and valve 36 closed. Valve 42 may be closed and valve 32 opened. With the compressor operating, retort 1 may be pumped down to atmospheric pressure. It is now in condition for opening and removal of the product.
- 55 The apparatus which has been described results in extremely rapid freezing, permitting a

chicken to be frozen solid in about 15 minutes. This rapid freezing is brought about by the extremely low temperature involved and the intimate contact between the freezing medium and the product to be frozen. Due to the efficiency of the apparatus, its capacity is high and the investment relatively low.

I claim:

1. In a freezing device, a product retort, a pipe from said retort communicating with a compressor, a condenser connected with said compressor, a liquefied refrigerant receiver connected with said condenser, a pipe communicating with said receiver and said retort, and a pump for returning liquefied refrigerant from said retort to said receiver as desired.

2. In a freezing device, a product retort, a pipe from said retort communicating with a compressor, a condenser connected with said compressor, a liquefied refrigerant receiver connected with said condenser, a pipe communicating with said receiver and said retort, a pump for returning liquefied refrigerant from said retort to said receiver as desired, and an air vent provided with a valve for preventing excessive pressures within the retort.

3. In a freezing device, a product retort, a pipe from said retort communicating with a compressor, a condenser connected with said compressor, a liquefied refrigerant receiver connected with said condenser, a pipe communicating with said receiver and said retort, a pump for returning liquefied refrigerant from said retort to said receiver as desired, an air vent provided with a valve for preventing excessive pressures within the retort, a valve positioned between said receiver and said retort, a pipe connecting said pump and said retort, a valve in said last mentioned pipe, and a pipe connecting said pump and said receiver.

4. In a freezing device, a product retort, a pipe from said retort communicating with a compressor, a condenser connected with said compressor, a liquefied refrigerant receiver connected with said condenser, a pipe communicating with said receiver and said retort, a pump for returning liquefied refrigerant from said retort to said receiver as desired, an air vent provided with a valve for preventing excessive pressures within the retort, a valve positioned between said receiver and said retort, a pipe connecting said pump and said retort, a valve in said last mentioned pipe, a pipe connecting said pump and said receiver, and

means including an air pump having means communicating with said retort for exhausting air from said retort.

5. In apparatus for quick freezing food in a liquefied refrigerant, a freezing retort, a liquefied refrigerant receiver connected with said retort by a pipe, a valve in said pipe, a pipe leading from said receiver to a compressor, said last-mentioned pipe provided with a valve, a pipe leading from said retort to said compressor, said last mentioned pipe provided with a valve, a pipe leading from said compressor to a condenser, a pipe leading from said condenser to said receiver, a pipe leading from said retort to an exhausting air pump, a pipe leading from said retort to a liquid pump, a valve in said pipe between said retort and said liquid pump, and a pipe leading from said liquid pump to said receiver.

6. In a quick freezing device, a closed retort having openable means for admitting product thereto, a liquefied refrigerant receiver communicating with the retort, means controlling the flow of liquefied refrigerant from the receiver to the retort, a compressor condenser circuit connecting the retort with the receiver, said compressor condenser circuit being adapted for withdrawing gaseous refrigerant from the retort and for delivering liquefied refrigerant to the receiver, and means for delivering liquefied refrigerant from the retort to the receiver.

7. In a quick freezing device, a closed retort having openable means for admitting product thereto, a liquefied refrigerant receiver communicating with the retort, means controlling the flow of liquefied refrigerant from the receiver to the retort, a compressor condenser circuit connecting the retort with the receiver, said compressor condenser circuit being adapted for withdrawing gaseous refrigerant from the retort and for delivering liquefied refrigerant to the receiver, and means including a liquid pump for delivering liquefied refrigerant from the retort to the receiver.

8. The method of quick freezing food products which comprises submerging the food in a liquefied refrigerant in a closed system under pressure, continuously withdrawing gaseous refrigerant, continuously returning liquefied refrigerant at a substantially constant low temperature until completion of the freezing process and thereafter withdrawing all of the liquefied refrigerant from the system.

CHARLES T. WALTER.
